WINE RACK

James Daniel Horney, 715 Cedar Crest Lane,
Cincinnati, Ohio 45230

Filed Oct. 3, 1972, Ser. No. 282,199

Term of patent 14 years

Int. Cl. D6—04

U.S. Cl. D7—71

FIG. 3

FIG. 2

FIG. 4

FIG. 1 is a perspective view of a rack embodying my new design.

FIG. 2 is a front elevational view of the rack depicted in FIG. 1. The rear elevational view is identical to the front elevational view.

FIG. 3 is a top plan broken section view of the rack of FIG. 1. The top plan view and the left side elevational views are identical.

FIG. 4 is a bottom plan broken section view of the rack of FIG. 1. The bottom plan view and the right side elevational view of the rack are identical.

I claim:

The ornamental design for a wine rack, as shown.
